UNITED STATES PATENT OFFICE

AMANDA M. LOUgee, OF BOSTON, MASSACHUSETTS.

FIREPROOF WIRE.

No. 809,811.

Specification of Letters Patent.

Patented Jan. 9, 1906.

Application filed November 5, 1903. Serial No. 179,929.

To all whom it may concern:

Be it known that I, AMANDA M. LOUgee, a citizen of the United States, residing in Boston, county of Suffolk, State of Massachusetts,

5 have invented an Improvement in Fireproof Wire, of which the following description, in connection with the accompanying drawings, is a specification, like letters on the drawings representing like parts.

10 My invention is manufactured as a single article to take the place of the hitherto usually separated insulated electric wire and conduit, and has for its objects the provision of great durability, flexibility, simplicity, and 15 cheapness of manufacture, high insulating and fireproof and preferably waterproof character, besides other objects or advantages, such as being unrestricted as to length in manufacture, &c., all as will appear more at 20 length from the following description.

My invention will be more readily apprehended if it is borne in mind that the present custom in the trade is to provide a separate conduit to receive the conducting-wire, the 25 latter usually being "fished" through in a laborious and expensive manner, resulting frequently in kinks or other defects in the wire itself, leading to possible short-circuiting and other disaster, while also the fishing process 30 frequently tears out the paper or other lining in the conduit and pulls off the covering of the wire and at best is expensive in labor, apparatus, and product, prevents perfect insulation, is limited as to the length of the 35 conduit, &c.; and accordingly it is the object of my invention to avoid all the above disadvantages and secure various additional advantages by constructing as a whole a conductor-wire (which may be of the usual in-

40 sulated kind commonly found in the market) having a fireproof covering of asbestos or equivalent substance incased in a flexible armor or protector and secured integrally or non-detachably together and capable of use 45 with the same convenience of application as a simple wire, while at the same time meeting the requirements of the fire underwriters as to fireproof, waterproof, insulating, and other qualities.

50 Without discussing the invention in a preliminary way further at this point reference is made to the accompanying drawings, where I have shown a preferred embodiment of the invention, the latter being more particularly 55 defined in the appended claims, taken in connection with the following description.

In the drawings, Figure 1 is a view in side elevation, parts being broken away for convenience of illustration. Fig. 2 is a similar view showing a modification.

60

In the drawings I have shown a medium size of my "single-article device," (as it may be called to designate one of its distinguishing characteristics,) and in Fig. 1 I have shown the same bent for indicating the extreme pli-

65

ability and in its preferred form permanence of pliability of the article, which may readily be bent around a corner or follow any particular configuration required by external or internal use. By my invention I provide in

70

a single article an armor-conduit containing an insulated fireproof, &c., conductor capable of internal and external use in all the positions which have heretofore required the usual lead or iron pipes in which the specially-

75

prepared wires have been fished or inserted, or, in other words, this single article meets in and of itself all the requirements which have heretofore called for laborious and expensive 80 separate constructions, difficult labor, and im-

perfect results when combined. The article

just as it is shown in Fig. 1 is ever ready to be simply put in place wherever desired, either for interior or exterior work, and at once meets all the requirements of the fire 85 underwriters as to indestructible character of armor, moisture-proof character, fireproof and durable qualities, permanence of position, resistance to the attacks of the elements, mice, 90

fire, or abrasion, &c.

95

Referring more particularly to the construction, it will be seen that at the center is any usual or preferred kind of wire or conductor *a*, preferably of the ordinary insulated kind, covered with rubber compound *b* and fabric

100

covering or other protector *b'*, on which is woven or otherwise permanently secured in the process of manufacture a fireproof jacket *c*, preferably of asbestos. An armor or reinforcing covering *d* is secured on the asbestos

105

by any suitable means, preferably by cement *e*, which may have an insulating character, such as a rubber compound, the cement also preferably permeating the meshes of the armor *d* when the latter has an open-work

110

character, and the whole is then coated, preferably with a fireproof compound *f*, which may be fireproof paint. I make no claim to any of the substances used nor to their arrangement with relation to each other considered alone, but wish it understood that my invention resides rather in providing the fire-

- proof-wire construction explained as an integral whole or single article of manufacture.
- The various portions may be applied by any usual or preferred machinery or other method—as, for example, the coverings *b c e* may be applied in plastic or partially plastic condition. The woven portions *b* (and *c* when applied as a woven covering) and *d* are woven directly in place as the manufacture proceeds, so that the article may be produced of any length desired and when finished presents a solid composite appearance as distinguished from detachable members. Also the weaving proceeds in a spiral or oblique manner, as shown, thereby giving greater flexibility and tending to maintain the parts in a compact and substantially solid relation mechanically in addition to the cementitious and other binding elements employed.
- Various portions of the article may be omitted, and instead of some of the portions others may be used. For instance, in Fig. 2 I have omitted the cement layer *e* and have shown a metal jacket or armor *d* instead of the woven-wire armor *d*, this covering *d* being applied in any manner desired—as, for instance, the tube may be immersed or passed through molten metal, or the latter may be deposited electrically or may be made in any metallic form that will have flexibility, the idea being to have a thin flexible protector capable of withstanding abrasion, &c., and of meeting the various requirements of the fire underwriters.
- I prefer the closely-woven-wire armor *d*, as it is capable of repeated bending without injury, can be woven very tightly in place, is extremely durable, and is sufficiently rough to embed itself in the cement or asbestos or whatever may be beneath it, and offers an excellent surface for retaining the outer coating of the enamel, fireproof paint, rubber, &c., which may be applied as an external finish and protector. Moreover, this armor of closely-woven wire coöperating with the interior construction entirely prevents danger from flaming fire therefrom, as it holds the insulation in a smothering grip. Another important advantage resulting from the close binding in of the conductor and the inclosed layers is that the swelling and bursting of the insulation are prevented and the conductor-wire is held intact as a conductor even under great heat, and likewise longitudinal strain on the insulation is prevented, tending to cause gaps therein and to render the insulation porous. In the usual insulated wire disastrous results are produced by the combination of two strains, an outward strain and a lengthwise strain, which are due to heat, bending, &c., these strains together resulting in the rapid deterioration of the insulation, covering, &c., whereas in my construction the closely-woven armor holds everything in undisturbed position, preventing both stretching and bulging,

and hence preventing the weakening and perforation of the insulation, and also preventing the ductile copper wire changing size, and hence its resistance, when highly-heated by an overload. The woven-wire jacket or armor *d* also provides an efficient conductor for a return-current, especially when insulated on both sides. This outer coating *f* may be of any color to suit the situation where the insulated fireproof wire is used, thereby rendering it feasible to run this wire both inside and outside a wall, along cornices, and, in fact, wherever convenience may suggest, as it can readily be painted to correspond to the adjacent surface, and as the entire article is small (as compared with the constructions commonly employed heretofore) and capable of being bent to any shape its neatness, artistic effect, and universal adaptability will be apparent.

When asbestos is used as the main fireproofing element, I prefer to employ the cement layer *e*, as explained, thereby incasing the asbestos in such a manner that it cannot yield to its tendency to absorb moisture, and in general I prefer to employ a waterproof layer or layers at or adjacent to the external covering of the article.

In addition to the non-separable unitary character given to the article as a whole by the mechanical process of weaving and molding the layers in place I intend to use in certain embodiments of my invention cementitious substances or compounds between or contained in the various layers for rendering them more permanently and solidly united and for rendering the conduit-wire as nearly homogeneous as its general structure will permit.

It will readily be seen without further explanation that by manufacturing the entire article as a whole instead of preparing its parts to be placed on the market separately not only is there a great saving of labor, &c., but it may be made of any indefinite length required, all inconvenience, danger, and expense of fusing the interior portions into or through an external tube or enveloping portion are avoided, there are no intervening spaces (as there are in the case of separate wire and conduit fished together) for the collection of moisture, air, &c., which under the influence of the electric current would tend rapidly to deteriorate and break down the entire structure, and the general construction is such that extreme flexibility, permanence, and durability are secured.

As already intimated, I do not limit my invention to the precise details set forth, as many variations may be resorted to without departing from the spirit and scope of my invention, and also while I have mentioned definite substances and parts I intend my claims to include the various mechanical and chemical equivalents thereof when said substances and parts are mentioned.

Having described my invention, what I claim as new, and desire to secure by Letters Patent, is—

1. As an article of manufacture, a permanently-flexible armored electric conductor of indeterminate length having an external size adapted to the usual wiring requirements of office-buildings, and having its component parts held integrally and permanently together by adhesion, said parts including a wire, a fireproof jacket for the wire, a waterproof covering for said jacket, and a tightly-woven-wire covering provided internally and externally with a waterproof and fireproof covering of insulation.
2. As an article of manufacture, a permanently-flexible armored electric conductor of

indeterminate length having an external size adapted to the usual requirements of office-buildings, and having its component parts held integrally and permanently together by adhesion, said parts including a wire, an asbestos jacket for the wire rendered moisture-proof by an enveloping coating of cement, inclosed by a tightly-woven jacket of wire embedded on both sides in waterproof and fireproof insulation.

In testimony whereof I have signed my name to this specification in the presence of two subscribing witnesses.
